ENGLAND, ASSIGNEES TO THE ELECTRIC & ORDNANCE ACCESSORIES COMPANY,
LIMITED, OF BIRMINGHAM, ENGLAND.

ELECTRIC-CIRCUIT-CONTROLLING APPARATUS FOR TRAIN-LIGHTING AND SIMILAR SYSTEMS.

1,117,198.

specification of Letters Patent.

Patented Nov. 17, 1914.

Application filed July 24, 1911. Serial No. 640,219.

To all whom it may concern:

Be it known that we, EDWARD HERBERT MANN LANGLEY and ERNEST WALTER PRICE, both subjects of the King of Great Britain, 5 residing at Cheston Road, Aston, Birmingham, in the county of Warwick, England, have invented certain new and useful Improvements in or Relating to Electric-Circuit-Controlling Apparatus for Train-Lighting and Similar Systems, of which the following is a specification.

This invention relates to electric circuit controlling apparatus for train lighting and similar systems and has reference to systems 15 in which two separate lighting circuits are each controlled by a switch, the two switches being of the kind that are so arranged and interconnected that when either switch is actuated it becomes automatically locked in 20 its new position and unlocks the other switch if the latter is locked. According as one or the other or both of the switches are actuated, variable lighting effects are obtained. Under ordinary conditions the switches are 25 actuated electro-magnetically, but provision is made for sometimes actuating them also by mechanical means, as for instance by a bar transversely movable with respect to the switches. Hitherto however, the movements 30 of such a bar for actuating the switches have not been as simple as is desirable. The chief object of the present invention is to provide improved switch apparatus of this kind and particularly to simplify the mechanical actuation of the switches.

According to the present invention the two switches are so arranged, that one is normally open and the other normally closed and means are provided whereby 40 each switch when actuated singly becomes locked in its new position; these means comprise link mechanism attached to each switch plunger and having a "dead-point" position, and an intervening member is provided for alternate actuation by the link 45 mechanisms so that only one switch can be locked at any one time. In order to actuate the switches mechanically when desired, the usual transverse bar is provided with two 50 actuating members, such as rollers, whereby a mere single longitudinal movement of the bar from one or other of two normal positions is able to effect the opening of the nor-

mally closed switch or the closing of the normally open switch while the movement of 55 the bar from one normal position to the other causes both switches to be actuated simultaneously.

In order that the said invention may be clearly understood and readily carried into 60 effect, the same will now be described more fully with reference to the accompanying drawings in which:—

Figure 1 represents diagrammatically a train lighting system, involving the use of 65 a dynamo and two sets of secondary batteries, and shows in elevation two electro-magnetic switches constructed and operating in accordance with the invention for the control of two lighting circuits forming part 70 of the system. The lower part of the system also shows means for actuating the switches mechanically. Fig. 1^a is a detached view of a detail hereinafter referred to. Fig. 2 is a detached sectional elevation, and Fig. 3 is 75 a plain elevation of the means for actuating the switches mechanically.

A represents the dynamo, B and B' are the two sets of batteries, the positive poles of which are connected together by way of 80 a resistance B² and are also connected to the positive brush of the dynamo.

C and C' are two series of lamps.

D and E are the two switches for controlling the two circuits of these lamps. The 85 switch D comprises a solenoid winding, the core or plunger D', the pair of contacts d d', and the bridge piece d'. Similarly the switch E comprises a solenoid winding, the core or plunger E', the pair of contacts e e', 90 and the bridge piece e'. The bridge pieces d' and e' are shown slidably mounted in guides d² and e² respectively in such a way that while being capable of actuation by their respective plungers, they have no mechanical connection with these plungers.

The means for locking the switch D, when actuated, comprise, in the construction shown in the drawings, an L-shaped piece D² mounted beneath the plunger D' on a stationary pivot D³ with one end connected by a link D⁴ to the plunger and the other end provided with a pin D⁵ adapted to bear upon one arm of a rocking member F common to the two switches. Similarly the 105 locking means of the switch E comprises the

2

L-shaped piece E², pivot E³, link E⁴, and pin E⁵. In the case of each L-shaped piece and connecting link, there is what may be termed a "dead-point"; the weight of the plungers, assisted if necessary by springs, tends to move the L-shaped pieces in one or other direction away from the "dead-point" position, but whereas in one direction this movement can take place freely, in the other direction all but a slight movement is checked; this check may be produced in any appropriate manner, for instance by suitably placed stops, such as F' in Fig. 1, or by so shaping the connecting links that projections, such as E', on them engage with the L-shaped pieces and prevent further motion as shown in Fig. 1^a. When either plunger is fully raised, the corresponding L-shaped piece and connecting link are moved to such a position that when the raising force on the plunger is removed the latter remains in its raised position owing to the link mechanism having passed its "dead-point" position and being prevented from moving farther as just described; in Fig. 1, the switch E is occupying this position. If the plunger D' happened to be locked in its raised position at the time when the switch E was actuated, the rising of the plunger E' would have caused the rocking member F to become tilted to such an extent that the L-shaped piece D² and connecting link D⁴ of the locked plunger D' would have been moved beyond their "dead point" position in the direction which permits of a free descent of this plunger. Hence, as hereinbefore stated, the locking of one plunger effects the unlocking of the other plunger, if locked. If both plungers are raised, both of the L-shaped pieces D² and E² have the same tendency to tilt the rocking member F, with the result that this member assumes an intermediate position, and therefore neither of the L-shaped pieces and their connecting links can pass beyond their "dead-point" in the direction which results in the locking of the corresponding plunger. Hence when the raising force on both plungers is simultaneously removed, these plungers both return to their normal position. It is to be observed that when both plungers are raised, the locking mechanism prevents their rising to the full extent.

In the case of electromagnetic actuation of the plungers, the master switch (not shown) that controls the energizing current, for the solenoid windings of the two switches may be such as to cause a mere momentary energizing of either solenoid or of both solenoids, since a continued energizing of the solenoid is unnecessary owing to the above described mechanical locking arrangement.

The means for actuating the switches of a coach mechanically, for instance during

periods when the coach is detached from the rest of the train, comprise a pair of auxiliary plungers G and H situated beneath the main plungers D' and E' respectively, and adapted to be thrust upward at the requisite intervals against the pins that connect the links D⁴, E⁴, to the main plungers. The transversely slideable bar J for actuating these auxiliary plungers is provided with two rollers G' and H' adapted for engagement with one or other or both of the auxiliary plungers. The distance between the axes of the rollers G' and H' is equal to the distance between the axes of the aforesaid auxiliary plungers G and H, and the usual springs control the sliding bar so that it normally assumes one or other of two idle positions in which one or other roller is in the space between the plungers. Pins J' J' are fixed to the bar J for engagement with the end plates J² of a slideable buffer J³ on which the adjacent ends of the controlling springs bear. If the bar in Fig. 1 is thrust to the right, the pin J' pushes the buffer J³ to the right so that immediately the bar is released the springs return it to its former position. By moving the bar from the idle position shown in Fig. 1 to that shown in Fig. 2, the other pin is brought up close to the buffer so that further movement of the bar toward the left produces a distortion of the springs again, with the result that when the bar is released the springs return it to the idle position shown in Fig. 2. The bar may be provided with a handle at one or each end and stops are also provided to prevent the bar from being moved beyond certain limits. The bar cannot be moved to the right more than to bring the roller H' vertically below the auxiliary plunger G; and the bar cannot be moved to the left more than to bring the roller G' vertically under the auxiliary plunger H. Hence a simple movement of the bar to the extreme right causes the auxiliary plunger G to be raised by the roller H' and the switch D to be opened (and the switch E unlocked and therefore opened also, if it was previously locked), the result being that both lighting circuits are broken; a simple movement of the bar to the extreme left causes the auxiliary plunger H to be raised by the roller G' and the switch E to be closed (and the switch D unlocked and therefore closed also if it was previously locked), the result being that both lighting circuits are closed; and a simple movement of the bar from the position shown in Fig. 2 to that shown in Fig. 3 or vice versa causes both auxiliary plungers to be raised simultaneously and lowered simultaneously resulting in the switches assuming their normal positions, namely the switch E open and the switch D closed, the result being that only one lighting circuit is closed. Since the locking mechanism pre-

vents the main plungers from both occupying their raised position simultaneously to the full extent, the auxiliary plungers may be of a slightly yielding character, as shown

5 clearly in Fig. 2, to allow of the two rollers passing under them simultaneously; the degree to which the said auxiliary plungers can yield is not, however, sufficient for the yielding property to be effective when either

10 of the main plungers is to be fully raised.

We claim—

1. Switch apparatus comprising a normally closed solenoid switch, a normally open solenoid switch, an L-shaped piece pivoted below each solenoid plunger, a link connecting each plunger with one end of the corresponding L-shaped piece in a manner

15 that provides a dead-point position, means for preventing free movement of each link and L-shaped-piece from the dead-point position in one direction, and means for preventing both L-shaped pieces and their respective links from assuming the dead-point

20 positions at the same time, said means being interposed between the two L-shaped pieces for actuation by the free ends of these pieces.

2. Switch apparatus comprising a normally closed solenoid switch, a normally open solenoid switch, an L-shaped piece pivoted below each solenoid plunger, a link connecting each plunger with one end of the corresponding L-shaped piece in a manner

25 that provides a dead-point position, means for preventing free movement of each link and L-shaped-piece from the dead-point position in one direction, and a rocking member for preventing both L-shaped pieces and their respective links from assuming dead-

30 point positions at the same time, said rocking member being interposed between the two L-shaped pieces for actuation by the free ends of these pieces.

3. Switch apparatus comprising a normally closed solenoid switch, and a normally open solenoid switch, each switch comprising a pair of contacts, a bridge piece, a solenoid coil, and a plunger coöperating with but unconnected to the bridge piece;

35 in combination with an L-shaped piece pivoted below each plunger, a link connecting each plunger with one end of the corresponding L-shaped piece in a manner that provides a dead-point position, means for preventing free movement of each link and L-shaped-piece from the dead-point position in one direction, and a rocking member for preventing both L-shaped pieces and their respective links from assuming dead-

40 point positions at the same time, said rocking member being interposed between the two L-shaped pieces for actuation by the free ends of these pieces.

4. Switch apparatus comprising a normally closed solenoid switch, and a normally open solenoid switch, each switch comprising a pair of contacts, a bridge piece, a solenoid coil, and a plunger coöperating with but unconnected to the bridge piece;

45 in combination with an L-shaped piece pivoted below each plunger, a link connecting each plunger with one end of the corresponding L-shaped piece in a manner that provides a dead-point position, means for preventing free movement of each link and L-shaped-piece from the dead-point position in one direction, and means for preventing both L-shaped pieces and their respective links from assuming dead-point positions at the same time, said means being interposed

50 between the two L-shaped pieces for actuation by the free ends of these pieces.

5. Switch apparatus comprising a normally closed solenoid switch, and a normally open solenoid switch, each switch comprising a pair of contacts, a bridge piece, a solenoid coil, and a plunger coöperating with but unconnected to the bridge piece;

55 in combination with an L-shaped piece pivoted below each plunger, a link connecting each plunger with one end of the corresponding L-shaped piece in a manner that provides a dead-point position, means for preventing free movement of each link and L-shaped-piece from the dead-point position in one direction, and means for preventing both L-shaped pieces and their respective links from assuming dead-point positions at the same time, said means being interposed

60 between the two L-shaped pieces for actuation by the free ends of these pieces.

piece, a solenoid coil, and a plunger coöperating with but unconnected to the bridge piece; in combination with an L-shaped piece pivoted below each plunger, a link connecting each plunger with one end of the corresponding L-shaped piece in a manner that provides a "dead-point" position, means for preventing free movement of each link and L-shaped piece from its dead-point position in one direction, and a rocking member for preventing both L-shaped pieces and their respective links from assuming dead-point positions at the same time, said rocking member being interposed between the two L-shaped pieces for actuation by the free ends of these pieces.

5. Switch apparatus comprising a normally closed switch, a normally open switch, a plunger coöperating with each switch to actuate it, a bar transversely movable with respect to the plungers, means carried by the bar to actuate one or the other of the

65 plungers when the bar is moved from one or the other of two idle positions in a direction away from the other idle position, but to actuate both plungers when it is moved from either idle position toward the other idle position, means for automatically re-

70 turning the bar to one or the other of its idle positions when moved therefrom in a direction away from the other idle position and released, means for locking either switch, when actuated, in its new position, and means for insuring that only one switch

75 becomes locked at any one time.

6. Switch apparatus comprising a normally closed switch, a normally open switch, a resilient plunger coöperating with each switch to actuate it, a bar transversely mov-

80 able with respect to the plungers, rollers mounted on the bar at a fixed distance apart and in a position to bear against one or the other of the plungers when the bar is moved from one or the other of two idle positions

85 in a direction away from the other idle position, but to actuate both plungers when it is moved from either idle position toward the other idle position, springs for automatically returning the bar to one or the other of its

90 idle positions when moved therefrom in a direction away from the other idle position and released, means for locking either switch, when actuated, in its new position, and means for insuring that only one switch

95 becomes locked at any one time.

7. Switch apparatus comprising a normally closed switch, a normally open switch, each switch comprising a pair of contacts, a bridge piece, a solenoid coil and a plunger coöperating with but unconnected to the

100 bridge piece; in combination with an auxiliary plunger for coöperation with each solenoid plunger, a bar transversely movable with respect to the plungers, means carried

105

110

115

120

125

130

4
 by the bar to actuate one or the other of the auxiliary plungers when the bar is moved from one or the other of two idle positions in a direction away from the other idle position but to actuate both auxiliary plungers when it is moved from either idle position toward the other idle position, means for automatically returning the bar to one or the other of its idle positions when moved 10 therefrom in a direction away from the other idle position and released, means for locking each solenoid plunger in its new position when actuated by the corresponding auxiliary plunger, and means for unlocking 15 one solenoid plunger as the other is being locked and preventing both plungers from being locked if they are simultaneously actuated.

8. Switch apparatus comprising a normally closed switch, a normally open switch, each switch comprising a pair of contacts, a bridge piece, a solenoid coil, and a plunger coöperating with but unconnected to the bridge piece; in combination with a slightly resilient auxiliary plunger for coöperation with each solenoid plunger, a bar transversely movable with respect to the plungers, 20 25

rollers mounted on the bar at a fixed distance apart and in a position to bear against one or the other of the auxiliary plungers when the bar is moved from one or the other of two idle positions in a direction away from the other idle position, but to actuate both auxiliary plungers when it is moved from either idle position toward the other 30 35 40 45

In testimony whereof we affix our signatures in presence of two witnesses.
